UNITED STATES PATENT OFFICE.

JOHN GEORGE TAYLOR, OF DUNREA, CANADA.

PNEUMATIC STACKER.

SPECIFICATION forming part of Letters Patent No. 688,897, dated December 17, 1901.

Application filed June 13, 1901. Serial No. 64,371. (No model.)

To all whom it may concern:

Be it known that I, JOHN GEORGE TAYLOR, a subject of His Majesty the King of Great Britain, residing at Dunrea, county of Rock 5 Lake, Province of Manitoba, Canada, have invented certain new and useful Improvements in Pneumatic Stackers; and I do hereby declare that the following is a full, clear, and exact description of the invention, such as will

enable others skilled in the art to which it appertains to make and use the same.

My invention relates to improvements in pneumatic stackers for grain-separators and threshing-machines; and the object in view 15 is primarily to save the chaff and some of the tailings from passing off with the straw, thus making the chaff, &c., available for use during the winter-time as feed for the farmer's live stock.

20 A further object is to arrange the parts in a way to discharge the chaff along with the straw, if desired, upon the straw-pile, and, furthermore, to simplify and cheapen the construction and to insure efficiency in operation.

25 With these ends in view the invention consists in the novel construction, combination, and arrangement of parts, which will be hereinafter fully described and claimed.

In the drawings hereto annexed, forming a 30 part of this specification, Figure 1 is a plan view of a pneumatic stacker constructed in accordance with my invention. Fig. 2 is a sectional plan view, the plane of the section being indicated by the dotted line 22 on Fig.

35 3 and the flexible chaff-discharging tube being shown in its horizontal and laterally-deflected positions by full and dotted lines, respectively. Fig. 3 is an enlarged vertical section through the rear portion of a grain-sepa-

40 rator or threshing-machine and representing my improved stacker mechanism in sectional elevation, together with the chaff-delivery tube connected operatively with the primary stacker-tube. Fig. 4 is a sectional view

45 through a universal joint adapted to couple the flexible chaff-delivery tube to the wind-trunk of the fan associated therewith. Fig. 5 is a detail sectional view illustrating the cut-off between the primary stacker-tube and

50 a part of the chaff-delivery tube.

The same numerals of reference denote like parts in each of the figures of the drawings.

5 designates a portion of a grain-separator or threshing-machine. 6 is the ordinary cleaning-shoe, 7 the grain pan or sieve, and 8 an endless straw-carrier. All these parts are ordinary in the art, and no novelty therefor is claimed in this application, the same being shown herein merely to enable others skilled in the art to understand the invention.

The rear portion 9 of the machine-frame supports a fan-casing 10, and said framework is also equipped with suitable shaft-bearings 11, in which is journaled the fan-shaft 12, the 65 same carrying a rotary fan or blower 13, whereby the fan may be rotated within the casing. For the purpose of distinguishing this fan from another fan which is associated with the primary stacker-tube I will on proper 70 occasions refer to the fan 13 as the "chaff-tube" fan. The shaft 12 is provided with two pulleys 14 15, around the latter of which passes a belt 16, that is adapted to be driven from any suitable working part of the grain-separator or threshing-machine. The other pulley 14 has an endless belt 18 fitted thereto and arranged to drive the stacker-tube fan 19, the same to be hereinafter more fully described. A wind-trunk 20 has its lower portion operatively connected with the fan-casing 10, while its upper portion is enlarged and curved so as to fit beneath that section of the machine-casing 5 which incloses the endless straw-carrier 8, all as more clearly shown by 85 Fig. 3. This wind-trunk thus has an enlarged tapering mouth arranged to partially inclose the rear open portion of the grain-separator, and the chaff and short straws which are delivered by the grain-pan 7 and 90 are blown from the cleaning-shoe 6 by the ordinary shoe-fan are adapted to be delivered into this wind-trunk 20. Furthermore, the wind-trunk tapers toward its rear portion, as clearly shown by Figs. 2 and 3, in order that 95 it may have the chaff-delivery-tube 21 connected thereto, said tube 21 consisting of a series of sections 21^a, 21^b, and 21^c. These series of sections are connected flexibly together by the pivotal joints 22 of a character 100 well understood by those skilled in the art, and the innermost section 21^b of this chaff-delivery tube is loosely fitted to the delivery end of the wind-trunk 20, as shown more par-

ticularly by Fig. 4. The flexible construction of the chaff-delivery tube permits it to be shifted laterally in a horizontal plane and either to the right or left, so that the outer end of this chaff-delivery tube may be arranged to deposit the chaff directly into a chaff-house, a bin, or any other place of storage. This adaptation of the chaff-delivery tube is a very advantageous feature of my invention, because it permits the chaff to be delivered from the separator directly into the place of storage without requiring the attention or services of an operator, and the chaff is saved by discharging it from the separator independently of the straw, so that the chaff may be utilized during the winter season as feed for the farmer's stock.

I do not limit myself to any particular or detailed construction of the chaff-delivery tube; but this tube should be of such a nature that it may be swung laterally in a horizontal plane, as described, and it should also be capable of a flexion movement in a vertical plane, to the end that the extremity of the tube may be connected operatively with the primary stacker-tube 23.

I will now proceed to describe one embodiment of means by which the tube 21 may be swung upwardly to the position shown by Fig. 3.

24 designates a carrier-ring having the arms 25, which are bolted or otherwise fastened to the wind-trunk 20 in a manner to sustain the carrier-ring 24 firmly in position around the wind-trunk and the member 21^b of the flexible tube 21. This carrier-ring has the slots 26, in which are loosely fitted the friction-rollers 27, that are mounted at the outer ends of the plates 28, the latter being firmly secured to the member 21^b of said flexible tube. It is evident that the rollers 27, which are supported by the plates 28 on the flexible tube, may be made to travel in the slots 26 of the carrier-ring for the purpose of giving a semirotary movement to the tube member 21^b of the flexible tube in order that the latter may be shifted to the position indicated by Fig. 3, wherein the pivots 22 between the tube-sections permit said flexible tube to be raised or lowered. Under this adaptation of the flexible tube the outer member 21^c thereof may be brought into operative relation to a short fixed nozzle 29, which is provided on the under side of the stacker-tube 23 and is arranged to inclose an opening 30, provided in the under side thereof. A coupling band or sleeve 31 is arranged to inclose the adjacent ends of the nozzle 29 and the outer member 21^c of the tube, said coupling-band being loosely connected, as at 32, to the nozzle and having a detachable fastener 33 connected with the tube member 21^c of the chaff-delivery tube.

It is evident that the chaff blown through the wind-trunk 20 by the action of the fan 13 may be carried by the flexible tube 21 into the stacker-tube 23 when said parts are ad-

justed as shown by Fig. 3; but the fastener 33 may be disengaged in order to release the flexible tube, and the latter may then be lowered and given a semiturn on the wind-trunk in order to restore the chaff-delivery tube to either of the positions indicated by full and dotted lines in Fig. 2. When the flexible tube 21 is disconnected from the stacker-tube 23, the opening 30 in the latter is closed by means of a cut-off 34, the latter being shown in Fig. 5 as a slideable damper; but of course the style of cut-off may be changed.

36 designates a hood which has a swiveled or pivotal connection at 37 to the rear portion of the casing 5, whereby the endless straw-carrier 8 is arranged to deliver the straw directly to the hood. This hood is also adapted to swing horizontally in order to change the place of discharge of the straw, and to the outer end of the hood is connected a stacker-tube 23 by means of the hinge-joint 38. This hinge is located at the upper side of the hood in order that the stacker-tube may be folded over and upon the separator; but the lower part of the stacker-tube has a lip 39, which is arranged to lap under the hood. (See Fig. 3.)

The blast-fan 19 has its shaft 19^a supported in suitable hangers 40, which are secured to the machine-casing, and around this blast-fan 19 is arranged the casing 41, which is arranged to have its lower part 42 connected with the hood 36, whereby the fan 19 is adapted to be driven by the belt 18 from the fan-shaft 12, and the blast of air from said fan 19 is arranged to catch the straw as it drops from the endless straw-carrier 8, so as to carry the straw through the hood 36 and the stacker-tube 23.

It is thought that the operation and advantages of my invention will be readily understood from the foregoing description, taken in connection with the drawings.

Changes within the scope of the appended claims may be made in the form and proportion of some of the parts, while their essential features are retained and the spirit of the invention is embodied. Hence I do not desire to be limited to the precise form of all the parts as shown, reserving the right to vary therefrom.

Having thus described my invention, what I claim as new is—

1. In a pneumatic stacker, the combination with a separator, of primary stacker devices arranged to receive straw from said separator, a chaff-delivery tube having operative connection with the separator to receive the chaff therefrom, said tube being shiftable so as to discharge the chaff independently of the stacker devices, and means whereby said chaff-delivery tube may be connected to the primary stacker devices to deliver chaff thereto, as set forth.

2. In a pneumatic stacker, the combination with a grain-separator, a primary stacker-tube, a chaff-delivery tube, means for separably coupling the chaff-delivery tube to

said primary stacker-tube, and independent blast-fans arranged to individually deliver their blasts to the primary stacker-tube and the chaff-delivery tube, substantially as described.

3. In a pneumatic stacker, the combination of a primary stacker-tube having operative relation to a separator to receive the straw therefrom, a chaff-delivery tube having means whereby it may receive the chaff from a separator, independent blast-fans arranged to deliver their blasts to the stacker-tube and the chaff-delivery tube, respectively, and means for separably coupling the chaff-delivery tube to the primary stacker-tube, substantially as described.

4. In a pneumatic stacker, the combination with a primary stacker-tube arranged to receive straw from a separator, a wind-trunk expanded to partially embrace the chaff-exit of a separator, a flexible chaff-delivery tube connected with said wind-trunk and having means for separably coupling the same to the primary stacker-tube, and independent fans arranged to discharge their blasts to the stacker-tube and the chaff-delivery tube respectively, substantially as described.

5. In a pneumatic stacker, the combination of a hood having means for supporting the same on a separator in a position to receive the straw therefrom, a primary stacker-tube foldably connected to the hood, a blast-fan adjacent to the mouth of the hood and adapted to direct its blast into the stacker-tube, a wind-trunk having an expanded end arranged to embrace the chaff-exit from a separator, and a flexible chaff-delivery tube connected with said wind-trunk, substantially as described.

6. In a pneumatic stacker, the combination of a hood provided with means for pivotally supporting the same upon a grain-separator in a position to receive straw therefrom, a primary stacker-tube operatively related to said hood, a blast-fan arranged to direct its blast through the hood and into the stacker-tube, a wind-trunk expanded to embrace the chaff-exit from a separator, a flexi-

ble chaff-delivery tube connected with said wind-trunk, and a coupling for detachably connecting the chaff-delivery tube to the stacker-tube, substantially as described.

7. In a pneumatic stacker, the combination of a hood having means for connecting the same to a separator in a position to receive straw therefrom, a primary stacker-tube having an opening in its lower side, a cut-off for closing said opening, a fan arranged to deliver its blast through the stacker-tube, a wind-trunk expanded to embrace the chaff-exit from a separator, a blast-fan mounted to direct its blast into the wind-trunk, a chaff-delivery tube, and means whereby said delivery-tube may be operatively connected to the stacker-tube, substantially as described.

8. In a pneumatic stacker, the combination with a primary stacker-tube, of a wind-trunk expanded to embrace the chaff-exit from a separator, a flexible chaff-delivery tube, means for operatively connecting said flexible tube and the wind-trunk and permitting the former to have a semirotary movement on the latter, and coupling devices whereby said flexible tube may be operatively connected with the stacker-tube, substantially as described.

9. In a pneumatic stacker, the combination with a primary stacker-tube, of a wind-trunk expanded to embrace the chaff-exit from a grain-separator, a flexible chaff-delivery tube having means whereby its delivery end may be connected operatively with the primary stacker-tube, a carrier-ring mounted on the wind-trunk, and connecting devices between a member of the flexible chaff-delivery tube and the carrier-ring, whereby the former may be adjusted with a semirotary movement on the latter, substantially as described.

In witness whereof I have hereunto set my hand in the presence of two witnesses.

JOHN GEORGE TAYLOR.
